UNITED STATES PATENT OFFICE.

WEBSTER C. ESTES, OF BROOKLYN, NEW YORK.

DESIGN FOR A WOODEN STOPPER.

SPECIFICATION forming part of Design No. 27,780, dated October 26, 1897.

Application filed July 27, 1897. Serial No. 648,150. Term of patent 14 years.

To all whom it may concern:

Be it known that I, WEBSTER C. ESTES, a citizen of the United States, residing at Brooklyn, in the county of Kings and State of New York, have invented and produced a new and original Design for a Wooden Stopper, of which the following is a specification, reference being had to the accompanying drawings, in which—

10 Figure 1 is an elevation. Fig 2 is a vertical section, and Fig. 3 is a plan.

The general configuration of the wooden stopper is round, and the leading features of my design consist of the disk-shaped top with 15 corresponding edge beads and a central rib.

a represents the tapering sides to the body, and *b* the disk-shaped top, with parallel upper and under surfaces 2 3. The beaded periphery of the top comprises the edge beads *c c'*, preferably of corresponding size, and between these is a narrow central rib *d*.

What I claim is—

The design for a wooden stopper, substantially as shown and described.

Signed by me this 7th day of July, 1897.

WEBSTER C. ESTES.
